UNITED STATES PATENT OFFICE

2,259,590

VOTING MACHINE

Ransom F. Shoup, Ardmore, Pa., assignor to The
Shoup Voting Machine Corporation, Philadel-
phia, Pa., a corporation of Delaware

Application March 7, 1939, Serial No. 260,289

4 Claims. (Cl. 235—51)

This invention relates to voting machines and more especially to voting machines of the general type disclosed in the patent to Shoup, et al. No. 2,054,102.

In some states or communities, the election law provides that in certain elections such, for example, as a primary election, a voter may cast a vote for his first choice of one of a group of candidates and then if he desires, cast a vote for his second choice from such group of candidates, the second choice being the voter's preference after his first choice candidate receives sufficient votes to elect him.

In the event that a voter indicates a second choice without indicating a first choice, the law provides that his second choice shall be counted as a first choice for the candidate which the voter has indicated as his second choice. Also, in the event that the voter indicates both his first and second choice for the same candidate, only his first choice vote is counted. The result of the election is decided by a compilation of the first and second choice votes according to a predetermined formula.

An object of this invention is to provide in a voting machine of the type above referred to, mechanism which permits a voter to register a first choice and a second choice for a given office and which will separately register the number of votes each candidate receives as a first choice and as a second choice, there also being provision for preventing a voter from operating the second choice registering mechanism until after he has operated the first choice registering mechanism and for preventing a voter changing his first choice without simultaneously canceling the second choice made prior to changing his first choice.

Other objects, novel features and advantages of this invention will become apparent from the following specification and accompanying drawings, wherein:

Fig. 1 is a fragmentary rear elevation of a voting machine embodying the invention;

Fig. 2 is a view partly in section similar to Fig. 1 but more fragmentary and on a larger scale, illustrating indication of a first choice by a voter;

Fig. 3 is a view generally similar to Fig. 2 illustrating indication of both a first choice and a second choice by the voter;

Fig. 4 is a view generally similar to Fig. 1, illustrating a modification;

Fig. 5 is a fragmentary view generally similar to Fig. 1 on a larger scale and partially in sec-

tion, illustrating certain details not shown in Fig. 1, and

Fig. 6 is a section substantially on the line 6—6 of Fig. 5.

5 In the following description, the reference characters used correspond in so far as practical with the reference characters used in Shoup, et al, Patent No. 2,054,102 and Shoup Patent No. 2,191,086 in which is disclosed more in detail 10 and claimed certain construction herein shown and described for the purpose of making clear the present invention.

As shown in Fig. 6, spindles 38 have their rear ends journalled in vertical straps 40 and at their 15 front ends are provided with handles 30. Each spindle is provided with a gear 43 operatively connected to a counter 44, all as described in said Patent No. 2,054,102 and in Shoup Patent No. 2,140,336. Also, each spindle is provided with a 20 pair of arms 59 and 59' interconnected by a pin 59b to which is attached a draw bar 61. The draw bars 61 pass between rollers 62 having their ends projecting into vertical grooves provided in a support 42 and being of reduced diameter centrally. Every fifth roller 62 is provided with a central bore through which apertures in the support 42 may be passed a pin 63 for fixing such roller against bodily movement. The rollers 62 between fixed rollers are capable of limited relative movement and each draw bar 61 is provided with a head or wedge 64 adapted to be drawn between a pair of rollers 62 upon operation of the spindle 38 to which it is attached through a draw bar 61. Each draw bar is of reduced width just to the left of the head 64, so that it lies in the space formed by the reduced central portions of the rollers 62 to permit the ends thereof to contact with each other except when the head 64 is moved between them by operation of a spindle. The above arrangement corresponds to the spindle interlock of the aforementioned Patents Nos. 2,054,102 and 2,191,086.

45 Assume that it is desired to condition the machine for registering first and second choices at a two-party primary in which one party has four candidates running for a particular office and the other party has three candidates running for such office. The upper four spindles of the extreme right column are allotted to the group of four candidates for first choice voting and the upper three spindles of the extreme left column are allotted to the group of three candidates for first choice voting (Fig. 1). The top spindles of the second, third and fourth columns from the

right are allotted for second choice voting to the candidates other than the one to whom the top spindle of the extreme right column is allotted for first choice voting and similar allotment is made of the second, third and fourth spindles from the top of the second, third and fourth columns from the right and the first, second and third spindles from the top of the second and third columns from the left. For the sake of clearness, the top four spindles in the extreme right column and the top three spindles in the extreme left column are labeled A, B, C, D, E, F, and G to indicate that they are allotted to candidates A, B, C, D, E, F and G for first choice voting. The upper four spindles of the second, third and fourth columns from the right and the upper spindles of the second and third columns from the left are labeled in the proper manner with the letters *a*, *b*, *c*, *d*, *e*, *f* and *g* to indicate the spindles allotted respectively to the candidates A, B, C, D, E, F and G for second choice voting. In each horizontal row of each of the two groups, the second choice spindles are allotted to the candidates of the group other than the one to whom the first choice spindle is allotted.

Figs. 5 and 6 illustrate structure common both to this application and Shoup Patent No. 2,191,086 which, while not a part of the present invention gives a clearer understanding of the operation of the machine. Plates 59a are attached to the arms 59' by the pin 59b extending through a slot in each plate and are adjustable into different positions. Straight ticket bars 190 are supported by swinging links 191 and are attached by links 198 to pivotally supported plates 197 having slots through which extend the pins 203. The straight ticket bars 190 are also adapted for co-operation with the plates 197 to lock the columns of spindles against operation in one position of the straight ticket bars and to release such spindles for operation in another position of such bar. In Fig. 5, the straight ticket bar is in position to be engaged by the plates 59a to prevent operation of the spindles and is held in such position by mechanism not shown herein, but fully described in said Patent No. 2,191,086. The pin 203 is arranged in the section 200 of the slot so that it does not interfere with downward movement of the bar 190.

To each spindle are attached arms 301 interconnected a pin 302 extending parallel to the spindle. The arms 301 for each first choice spindle are so arranged on the spindle that the pin 302 lies below the level of the spindle axis in both its voted and unvoted position. The arms 301 for each second choice spindle are so arranged on the spindle that in the unvoted position of the spindle, the pin 302 is at the same level as the spindle axis and is swung to a lower level upon rotation of the spindle into voted position. The pins 302 on the arms 301 for the first choice spindles are spaced from the spindle axes a greater distance than the pins 302 on the arms 301 for the second choice spindles. Horizontal bars 303 rest upon horizontal rows of spindles and are slidably thereon. Each bar has a recess 304 in which is received the pin 302 of a first choice spindle with the arms 301 overlying the sides of the bar and is movable by rotation of the first choice spindle between its normal position shown by the second bar from the top in Fig. 2 (unvoted position of the spindle) and the position shown by the top bar in Fig. 2 (voted position of the spindle). The recess 304 is of greater

length than the diameter of the pin 302 so as to permit additional movement of the bar 303 from the position shown by the top bar in Fig. 2 into the position shown by the top bar in Fig. 3, such movement being effected by actuation of a second choice spindle. Each bar also is provided with a plurality of notches 305 so arranged that after a bar 303 has been moved to its out-of-normal position by movement of the associated first choice spindle from unvoted to voted position, the notches 305 underlie the pins 302 of the second choice spindles, thus providing a free path for such pins. However, when a bar 303 is in normal position, the upper edge of the bar lies in the path of the pins 302 of the second choice spindles to prevent actuation thereof.

Each first choice spindle is provided with an arm 306 through which extends the pin 302 of the arms 301 for such spindle and which in turn is attached to a pull bar 61'. The pull bars 61' are associated with a control interlock similar to the main interlock above described and consisting of rollers 62' mounted in channels in a support 42', every fifth roller being provided with a central bore through which and apertures in the support 42' may be passed a pin 63' for fixing such roller against bodily movement. The rollers 62' between fixed rollers are capable of limited relative movement and each draw bar 61' is provided with a head or wedge 64' adapted to be drawn between a pair of rollers 62' upon operation of the spindle to which it is attached through a draw bar 61'. Each draw bar is of reduced width just to the left of its head so that it lies in the space formed by the reduced central portion of the roller 62' to permit the ends thereof to contact with each other except when a head 64' is moved between them by operation of a spindle.

40 The main interlock is so conditioned that it will permit the operation of two but only two bars 61' attached to spindles allocated to the candidates of one party. The auxiliary interlock is so conditioned that it will allow the operation of only one bar 61' attached to a spindle allocated to the candidates of one party.

In Fig. 1 is illustrated the position of the various spindles upon entry of a voter into the machine, the straight ticket bars 190 for the four right-hand columns having been lowered to free the spindles in such columns. All the second choice spindles are locked by reason of the fact that the various bars 303 lie in their paths, and no one of them can be operated until after the operation of a first choice spindle. Assume that the voter actuates the first choice spindle A (Fig. 2). Such actuation pulls the corresponding wedge 64' between a pair of rollers 62', thereby locking out the remaining first choice spindles, and pulls the corresponding wedge 64 between a pair of rollers 62, thereby reducing to one the number of additional spindles which may be actuated. Also, the actuation of the spindle A effects movement of the corresponding bar 303 sufficiently to the left to place the notches 305 in the path of the pins 302 of the second choice spindles *b*, *c* and *d*. The remaining second choice spindles are, however, still locked as only one bar 303 has been actuated. Next, the voter actuates a second choice spindle in the same horizontal row as the spindle A, for example *b* (Fig. 3). Actuation of the spindle *b* effects movement of the corresponding pull bar 61 to bring a head 64 between a pair of rollers 62 and thus prevent actuation of any other second choice spindle in

the horizontal row. Also, actuation of the spindle **b** effects further leftward movement of the actuated bar **303** to bring the right-hand end of the slot **304** into contact with the pin **302** of the arm of the actuated first choice spindle.

After a voter has indicated his first and second choice as above described, the registration of the vote is effected in the same manner as fully described in said Shoup Patent No. 2,054,102 and the actuated bar **303** is returned to original position by the return movement of its corresponding first choice spindle. At the end of the voting period, each counter associated with a first choice voting spindle registers the number of first choice votes cast for the candidate to which such spindle was allotted and the figures registered by the counters associated with the second choice spindles for each candidate represents the distribution of the second choice vote for candidates as to preference after the first choice selection.

After a voter has indicated his first and second choice, he cannot change his first choice indication without at the same time restoring the actuated second choice spindle to unvoted position. This is due to the fact that as shown in Fig. 3, the right-hand end of the notch **304** engages the pin **302** associated with the actuated first choice spindle, while the pin **302** of the actuated second choice spindle engages the left-hand end of the notch **305** into which it has been turned. Thus, return of the first choice spindle to unvoted position as is necessary to make a change in the selection of the first choice results in the rightward movement of the bar **303** to its original position with concomitant counterclockwise movement of the actuated second choice spindle. The second choice spindle is returned to its unvoted position before the first choice spindle reaches such position, due to the longer arc traversed by the pin **302** of the first choice spindle by reason of the greater distance of such pin **302** from the axis of the first choice spindle. Thus, it is impossible for a voter to register only his second choice vote.

In Fig. 4 is illustrated a set-up for five candidates in which only three columns of spindles are required. In this modification, alternate spindles in the extreme right column are allotted for first choice voting and in the second and third columns from the right two horizontal rows of spindles are allotted for second choice voting for each first choice spindle. A bar **303** is provided for each horizontal row of spindles and pairs of bars are connected by plates **308** for simultaneous actuation. Operation of more than one first choice spindle is prevented by the spindle interlock above described and actuation of more than one second choice spindle likewise is prevented by the control interlock above described.

It is of course understood that various modi-

fications may be made in the arrangement above described without in any way departing from the spirit of the invention as defined in the appended claims.

5 I claim:

1. In a voting machine, a first spindle, a plurality of additional spindles arranged in a row with said first spindle, a bar slideable in a path parallel to but offset from said row of spindles, means including a lost motion connection for effecting bodily movement of said bar upon actuation of said first spindle, an arm on each additional spindle extending parallel to the length of said bar with the spindle in unvoted position and having a portion overlying one edge of said bar, and notches in said bar edge arranged to receive said arm portions only after movement of said bar by actuation of said first spindle into voted position whereby prior to actuation of said first spindle into voted position said arm portions are engageable with the edge of said bar to prevent actuation of said additional spindles and whereby after movement of said bar by actuation of said first spindle into voted position, actuation of any additional spindle effects movement of its arm portion into a notch in contact with a side wall thereof to cause further bodily movement of said bar, the extent of the lost motion existing between said bar and said first spindle being equal to the extent of movement of the bar effected by actuation of any additional spindle into voted position.
2. In a voting machine, the combination according to claim 1 characterized by the extent of movement of the bar effected by said first spindle being greater than that effected by any additional spindle.
3. In a voting machine, the combination according to claim 1 characterized by said lost motion connection comprising a recess in said bar and a projection on said first spindle arm extending into said recess with the recess being greater in length than the diameter of the projection by the extent of movement of the bar effected by actuation of any additional spindle into voted position.
4. In a voting machine, the combination according to claim 1 characterized by said lost motion connection comprising a recess in said bar and a projection on said first spindle arm extending into said recess with the recess being of greater length than the diameter of the projection and further characterized by said first spindle arm projection being at a greater distance from the axis of rotation than said additional spindle arm portions to effect greater movement of the bar by actuation of said first spindle into voted position than by actuation of any additional spindle into voted position.

RANSOM F. SHOUP.
